UNITED STATES PATENT OFFICE.

FREDERICK LINDMEIER AND JUSTUS LINDMEIER, OF OAK PARK, ILLINOIS.

HUMIDIFIER SYSTEM AND APPARATUS.

1,291,946.

Specification of Letters Patent. Patented Jan. 21, 1919.

Application filed November 23, 1917. Serial No. 203,490.

To all whom it may concern:

Be it known that we, FREDERICK LINDMEIER and JUSTUS LINDMEIER, citizens of the United States, residing at 735 North Grove 5 Ave., Oak Park, in the county of Cook and State of Illinois, and 819 Woodbine Ave., Oak Park, in the county of Cook and State of Illinois, respectively, have invented a certain new and useful Improvement in Humidifier Systems and Apparatus, of which the following is a full, clear, concise, and exact description, reference being had to the accompanying drawings, forming a part of this specification.

Our invention relates to humidifier systems and apparatus for hot water and steam radiators. One feature of the invention relates to the method of maintaining a proper level of water in the humidifier sections of radiators. Another feature of our invention relates to a simple device for preventing the ingress of water when the atmosphere is already sufficiently humid. Another feature of the invention relates to the method and apparatus for extracting water from a steam radiator. Another feature of the invention relates to the method of automatically replenishing the water in a steam heating system, and another feature of the invention relates to the method of indicating when the water falls below a desired level in a hot water heating system.

Our invention is particularly adapted for use with radiators of the type illustrated in our application Serial No. 150,391, filed February 23, 1917, relating to combined humidifiers and radiators. It is to be understood, however, that certain features of the invention are applicable to devices coming within the purview of the said co-pending application.

Still further features of the invention will be hereinafter pointed out in the following specification.

Our invention is illustrated in the accompanying drawings, in which—

Figure 1 is a radiator into one end of which is to be fitted a tank having water level controlling mechanism therein;

Fig. 2 is an end view of the radiator shown in Fig. 1;

Fig. 3 is a sectional view taken on the line 3—3 of Fig. 2;

Fig. 4 is an enlarged drawing of the water level controlling mechanism assembled;

Fig. 5 is a section through the hygrostatic element of the water level controlling mechanism;

Fig. 6 is a section taken on the line 6—6 of Fig. 4;

Fig. 7 illustrates our invention applied to a hot water system;

Fig. 8 is an enlarged view of the dial and circuit controlled mechanism of Fig. 7;

Fig. 9 is a section on the line 9—9 of Fig. 8; and

Fig. 10 illustrates our invention as applied to a steam heating system.

Similar characters of reference refer to similar parts throughout the several views.

The radiator illustrated in Fig. 1, and the type with which we prefer to use our invention, is provided with three humidifier sections. These sections appear externally substantially the same as the remaining sections of the radiator, but are provided with abutting flanges 11 and 12 which, when the parts are clamped together, form a chamber within the heating elements of the radiator. The end radiator sections of the humidifier group are preferably provided with integrally cast walls, such as shown at 13 and 14, which serve to complete the ends of the humidifier tank.

Humidification of the atmosphere is brought about by evaporation from large moisture surfaces, wherefore we have found it advantageous to insert sheets, 15, of absorbent material such as asbestos, these being extended considerably above the level of the tank walls so that the air in circulating upwardly through the radiator will carry off large quantities of moisture from the surfaces of these absorbent members. Within one or more of the humidifier sections is placed the mechanism which controls the supply of water to the tank, and which also controls the level of the water and prevents the water from flowing at all when the atmosphere is already sufficiently humid. This mechanism comprises a U-shaped pipe or tube 17, which constitutes a supporting frame for the controlling apparatus. Between the arms of this frame and near the base thereof is a float 18 pivoted at 19 and provided with an upwardly extending bearing support 20. Above this float and pivoted in the bearing support is an arm 21 which extends laterally on each side of the bearing support 20. One end of this arm is

100

95
100
105
110

5 pivotally connected to the cross frame members 22 by means of a pivot pin 23, this pin also passing through one end of an arm 24. Springs 25 extend between the protruding
 10 ends of pins 26 and 27 carried respectively at the extremities of arms 21 and 24, the arrangement being such that the springs tend to collapse the two arms 21 and 24 upon one another. As the float 18 rises and falls it causes the intermediate parts of the springs
 15 25 to pass above and below the pivot 23 so that the arm 24 is caused to have either a somewhat definite downward pressure or a somewhat definite upward pressure at its extremity. The extremity of arm 24 is attached to the valve rod 30 having an arm 31 extending laterally and upwardly, the upper end of which is pointed and arranged to bear upon the valve seat 32 when the rod is
 20 pressed upwardly and to be withdrawn from the valve seat when the rod is pressed downwardly, whereby water will be admitted through the valve until the float has by rising caused the reversal of the valve rod position and the consequent closing of the valve.

On account of the high temperature at which this humidifier is operated moisture will be driven into the atmosphere notwithstanding the already sufficiently humid condition of the atmosphere unless means are provided for preventing the ingress of water under the aforementioned humid atmospheric conditions. For this purpose a hygrostatic controller is mounted upon the upper end of one of the arms of the U frame. This controller comprises two strips of material 35 and 36 which has a high degree of expansion and contraction for slight temperature changes. Any material which is impervious to moisture may be used for this purpose and ordinarily hard brass has been found to be satisfactory. Between the two strips of material 35 and 36 is inserted a third strip of material 37 which must be of low heat conductivity. We have found mica to be highly satisfactory for this purpose. By means of screws or rivets 38, which preferably pass through heat insulating bushings 39, the two strips 35 and 36 are rigidly attached together at frequent intervals throughout their length so that the slight expansion or contraction of one of these elements causes the bowing of the free end 40 of the device either upwardly or downwardly, depending upon whether the lower or the upper of the two elements 35 and 36 is the warmer. The assembled elements 35, 36, and 37 are attached to a rocker support 41 by means of two screws 42 and 43 which can be adjusted so as to bring about the proper normal position for the free end 40 of the hygrostatic element.

Along the under side of the member 36 of this hygrostatic element is a wick 45, this

wick being preferably cemented to the element 36 and preferably covering substantially the whole under surface thereof. This wick is forced down into the left arm of the U shaped frame and is so closely packed 70 therein that the water of the heating system will pass through the wick only very gradually, and preferably only substantially fast enough to overcome the evaporation in the exposed portion of the wick.

In the operation of this structure the wick 45 remains constantly wet and since evaporation continuously occurs therefrom its temperature remains somewhat lower than the temperature of the hygrostatic element 35 80 separated therefrom by a good thermal resistor. So long as evaporation continues at a certain rate from the wick 45 the free end 40 of the hygrostatic element will be deflected downward due to the slight contraction of the member 36. When the atmosphere becomes so moist that the rate of evaporation is decreased the free end 40 of the hygrostatic element is caused to raise into engagement with the washer 90 46, which is rigidly carried by the valve rod 30, thus preventing the arm 31 from moving away from the seat 32 even though the float does drop by reason of the complete evaporation of the water in 95 the humidifier chamber. When, however, the atmosphere becomes less humid the evaporation from the wick becomes more rapid and the free end 40 moves downwardly opening the valve and permitting the humidifier 100 chamber to become refilled to the level at which the float again assumes control. The water which passes through the valve will trickle down the rod 30 and run off the lower end thereof without being deflected 105 outside the humidifier tank.

A cock 48 is provided near the end of the radiator at the point where the water enters the humidifier section so that the water may be manually cut off when desired.

Although the apparatus thus far described may be operated satisfactorily by connecting the pipe 49 with the city water supply, or any other suitable source, it is preferable, by reason of the saving in piping, to obtain the water for moistening the air directly from the heating system.

When the device is used in connection with a hot water heating system this may be done by connecting the pipe 49 into any 120 part of the hot water radiator, but when the device is used in conjunction with a steam heating system it is necessary to use steam which has condensed in the radiator. In order that an adequate supply of water may be 125 always on hand the tank 50 is provided beneath the radiator and sufficiently separated therefrom that its temperature will not be up to the boiling point of water. This tank is tapped into one of the legs of the radia- 130

tor, which under normal conditions is full of water which has been condensed in the radiator, or to some other low point of the radiator, whereby the tank 50 will be maintained at all times substantially full of water. This supply is necessary because of the intermittent character of the device which causes the humidifier sections to fill within a comparatively short time when the mechanism has been tripped by the lowering of the float 18. The distance between the base of the tank 50 and the point at which the water empties into the humidifier section is small and the steam pressure is relied upon to carry the water up the pipe 49.

When our device is to be used with a vacuum steam system the water supply is of necessity brought through independent piping as it cannot, under those circumstances, be obtained from the radiator system.

The large quantity of water taken from either a hot water or steam system by these automatically operating humidifiers make it important to provide automatic means for either indicating the necessity of an additional water supply or actually controlling the water supply. In a hot water system it is not essential to safety that the level be maintained as accurately as in a steam system. We, therefore, find it sufficient in hot water systems to provide a lamp 60 which is automatically displayed near the heater when the level of the water drops below a predetermined point. In order that the circuit of this lamp may be quickly closed and opened to prevent sparking a flat spring 61 is mounted between two posts 62 and 63, which are supported on the glass front of the water level indicator. This spring 61 is of slightly greater length than the distance between the posts 62 and 63 so that it bulges either on one side or the other of the straight line between the posts. A contact 64 is carried on the spring 61 so as to register with a contact carried by the post 65, also mounted in the glass of the indicator. The spring 61 has a projecting portion 66 which is slightly twisted so that the pins 67 and 68 will engage alternate sides thereof as the hand 69 moves either in a clockwise or counterclockwise direction. In this manner as the hand 69 moves in a clockwise direction it causes the contacts 64 and 65 to be quickly separated, and as the hand moves in a counter-clockwise direction upon the falling of the level of the water the spring 61 is deflected outwardly so as to cause the quick registration of the contacts 64 and 65.

In order to control the level of the water in a steam heater we provide a tank 70 having a float 71 therein which is connected by means of a lever 72 and rod 73 with a mechanism constructed exactly the same as the mechanism constituting a part of the valve control described in connection with Fig. 4,

the whole being such as to cause the valve pin 74 to be pressed upon the seat 75 to cut off the supply of water from the main 76 when the float 71 rises to a predetermined level and to again withdraw the pin 74 from its seat 75 when the float drops to a predetermined level. The upper part of the tank 70 is connected to the steam part of the heater by means of a pipe 77, whereas the lower part of the tank 70 is connected to the water portion of the heater by means of a pipe 78. By this device the water level is automatically kept within predetermined limits.

While we have described our invention with respect to certain details, it is to be understood that we do not wish to be unduly limited thereto, certain modifications being possible without departing from the spirit or scope of our invention.

Having thus described our invention, what we claim as new and desire to secure by Letters Patent of the United States is:

1. A humidifier system comprising a tank associated with a radiator, a connection for carrying water from the heating coils of the radiator to said tank, a valve controlling the flow of water through said connection, a float controlling said valve to maintain a substantially constant level of water in said tank, and a hygrostatic element for preventing the ingress of water when the atmosphere is already sufficiently humid.

2. In a humidifying system the combination with a radiator, of a tank associated therewith, a float in said tank, a valve controlled by said float, a hygrostatic element for preventing the opening of said valve when the atmosphere is already humid, and a pipe leading to said valve from a source of water supply.

3. The combination with a heating system, of means for humidifying the air heated by said system comprising a water tank, a valve controlling the supply of water to said tank, means controlled by the level of the water in said tank for opening and closing said valve, and a hygrostatic element for holding said valve closed when the air heated by said system is sufficiently humid irrespective of the level of the water in said tank.

4. A unit for a humidifier comprising a pipe connection provided with a valve seat, a support for said pipe connection, a valve coacting with said seat, a float pivotally mounted in said support and connected with said valve, and a hygrostatic element mounted on said support and having a lost motion connection with said valve.

5. A unit for a humidifier comprising a pipe connection provided with a valve seat, a support for said pipe connection, a valve coacting with said seat, a float pivotally mounted in said support and connected with

said valve, and a hydrostatic element mounted on said support and connected to said valve.

6. The combination with a radiator of a tank supported between the heating elements of said radiator, means for supplying water to said tank, and means located within said tank responsive to varying degrees of moisture in the air heated by said radiator, for 10 controlling the flow of water to said tank,

the said last named means coating with the means for supplying water to said tank.

In witness whereof, we hereunto subscribe our names this 16th day of November, 1917.

FREDERICK LINDMEIER.
JUSTUS LINDMEIER.
